and Co. ATTORNEY

UNITED STATES PATENT OFFICE

2,010,011

COMBINATION CONTAINER

John Colaizzi, Pittsburgh, Pa.

Application October 31, 1933, Serial No. 696,091

5 Claims. (Cl. 248—291)

The invention relates to a combination container and more especially to sanitary containers for holding soap, wash rags, garbage, etc.

The primary object of the invention is the provision of a device of this character, wherein a rack and a garbage pail holder can be supported beneath a kitchen sink and will be conveniently accessible, the rack being adaptable for receiving soap, sponges, brushes, cloths or other articles 10 usable for cleaning purposes, and when not in use will be so held as to be hidden from view and to assure a sanitary condition, while the garbage pail is movable to a position for the reception of garbage, trash or the like and normally is in closed 15 position and out of the way.

Another object of the invention is the provision of a device of this character, wherein the garbage pail is supported in a novel manner and is conveniently accessible by reason of the fact that when 20 the holder for the garbage pail is manipulated to give access to the pail the lid thereto will be automatically raised or opened and on the movement of the holder to normal position out of the way the lid will close.

A further object of the invention is the provision 25 of a device of this character, wherein the rack for the cleaning mediums and the garbage pail holder can be conveniently manipulated and are supported in a manner to render the same freely 30 accessible and when not in use thoroughly sanitary.

A still further object of the invention is the provision of a device of this character which is simple in construction, thoroughly reliable and 35 efficient in its purpose, readily and easily assembled and mounted for use, strong, durable, and inexpensive to manufacture and install.

With these and other objects in view, the invention consists in the features of construction, 40 combination and arrangement of parts as will be hereinafter more fully described in detail, illustrated in the accompanying drawings, which discloses the preferred embodiment of the invention, and pointed out in the claims hereunto appended.

45 In the accompanying drawings:

Figure 1 is a top plan view of the device constructed in accordance with the invention and supported upon a side wall beneath a sink (not shown), the rack for the cleaning mediums being 50 pulled outward for access thereto.

Figure 2 is a side elevation.

Figure 3 is a front elevation.

Figure 4 is an elevation of the support for the rack and garbage pail holder.

55 Figure 5 is a side view thereof.

Figure 6 is an enlarged fragmentary top plan of the same.

Figure 7 is an enlarged horizontal sectional view through one side member of the support, showing 60 in detail the manner of latching the rack when

pushed inwardly thereof, the section being taken on the line 7—7 of Figure 3.

Figure 8 is a perspective view of one of the side plates of the support.

Figure 9 is a detail fragmentary side elevation 5 showing the pail holder in normal position.

Figure 10 is a view similar to Figure 9 showing the pail holder tilted for access to the garbage pail to be held therein.

Figure 11 is an enlarged vertical longitudinal 10 sectional view through the check and return member for the pail holder.

Figure 12 is an end elevation thereof.

Figure 13 is a plan view of the rack removed 15 from the device.

Figure 14 is a side view thereof.

Figure 15 is a vertical transverse sectional view through the rack, showing the holders thereof for soap, sponge, cloths or other cleaning mediums.

Similar reference characters indicate corresponding parts throughout the several views in the drawings.

Referring to the drawings in detail, A designates generally a portion of a vertical wall of an enclosure and B diagrammatically a portion of a 25 kitchen sink supported by said wall. The device constituting the present invention is adapted to be disposed beneath the sink B and carried by the wall A, it including a stationary support having the spaced parallel horizontally arranged 30 side members 10 joining at their innermost ends and cross piece 11 provided with suitable openings 12 for fasteners (not shown) and used for securing the support upon the wall A. These side members have joined therewith angular braces 13 35 integral with a cross piece 14, the latter being also made fast to the wall. The pieces 11 and 14 have joined therewith intermediate thereof a channeled bar 15 which is vertically disposed and for a purpose presently described. 40

The side members 10, at their inner faces, are provided with guide flanges 16 for the fitting of a movable rack therewith and this rack is in the form of a skeleton drawer 17, its sides 18 being slidably fitted with the guide flanges 16. 45 The front 19 of the drawer 17 carries a handle 20 to permit the convenient pulling out and pushing in of such drawer in the support. The side members 10 carry spring snap latches 21, these being engageable in seats 22 provided in the sides 18 of the drawer 17 and functioning to frictionally latch the said drawer either when pulled outwardly or pushed inwardly. 50

Fitted within the drawer in suitable spaces 23 55 provided therein are holders 24 and 25, respectively, these being adaptable for the reception of soap, sponges, cloths or other cleaning mediums, the holders being arranged with soap trays 26 and such holders and trays being re- 60

movable from the drawer, when the occasion requires.

Provided on the outer faces of the side members 10 are loops 27 for detachably accommodating clips 28 on side cheeks or plates 29 which close the sides of the support, it being apparent that the cheeks or plates 29 are removable from said support.

Carried by the side members 10 intermediate 10 of their length are suitable socket pieces 30 for detachable mounting of depending hangers 31 between which is arranged a garbage pail holder 32 having a swinging arm 33 pivoted to said hangers at 34 for tilting or swinging movement. 15 The holder 32 carries a lid or cover 35 connected by a hinge 36 to the rearmost point of said holder for opening and closing movements, the foremost portion of the holder 32 being provided with a handhold 37. 20 The channeled bar 45 carries a cross pivot 33 for the hinging end 39 of a piston cylinder 40 having slidably fitted therein the piston 41, its stem 42 working through the said cylinder and being provided with a connector hook 43 engaged 25 with the holder 32. Surrounding the stem 42 within the cylinder 40 is a coiled tensioning spring 44, the cylinder 40 being fitted with an adjustable air escapement 45 at the hinging end 39 of said cylinder. Thus it will be apparent 30 that under the operation of the piston 41 within the cylinder 40 and the cooperating spring 44 with the air escapement 45, the pail holder 32, when tilted forwardly, will be checked and returned to normal upright position, the tilted position of the holder 32 being shown in Figure 10 and the normal upright position being shown in Figure 9 of the drawings. When the holder 32 is tilted, ready access may be had thereto for the reception of garbage in a garbage pail placed 35 within the holder. 40

Connected with the inner end of the drawer 17 is a chain 46 which is also connected to the center handle 47 on the lid 35, the chain 46 being of the required length that when the holder 32 is pulled to tilting position this chain will operate upon the lid 35 so that the holder will be opened automatically and by gravity the lid 35 will close when the said holder 32 is returned to normal upright position. It should be apparent that by reason of the length of the chain 46 it will not interfere with the pulling of the drawer 17 outwardly of the support and without disturbing the lid 35 when the said holder 32 is in normal upright position, this being apparent from Figures 1, 9 and 10 of the drawings. 55

The air trapped within the cylinder 40 will operate as a cushion upon the piston 41 to retard the quick action of the spring 44 when contracted by the outward tilting of the holder 32 so that this holder, when being automatically returned to upright position, will gradually assume that position from its tilted position.

The drawer 17, through the medium of the latches 21 engaging the seats 22, will be frictionally held inwardly of the support and when the holder 32 is tilted the chain 46 will be active upon the lid or cover 35 to exert a pull thereon and thus the holder 32 will be opened when in the tilted position. To each hanger 31 above the pivot 34 connecting the swinging arms 33 thereto is pivoted, at 48, one end of a link 49 which, at its other end, has the slot 50 and in this slot is received the pin 51 carried by the said arms

33 next to the link 49, so that on tilting the holder 32 forwardly, this link 49 will limit the throw or swinging movement of such holder, as will be apparent in Figure 10 of the drawings. The pin 51 on the arm 33 of the holder 32 is above the swinging axis of the link and is adapted for displacement in the slot 50 in the latter during the swinging of the holder 32. 5

It should be obvious that convenient access can be had to the drawer on the pulling outwardly 10 thereof for the use of the cleaning mediums as may be held thereby and also ready access may be had to the holder 32 for the placing of garbage within the garbage pail as contained therein, the garbage pail being not shown. 15

What is claimed is:

1. A device of the character described comprising a support for mounting upon and horizontally to a vertical wall and having spaced parallel side members, hangers depending from said side members, a garbage pail holder swingingly supported by said hangers, air cushioned tensioning means connected with said holder and said support to return the holder to normal upright position after tilting thereof, a hinged lid on said holder, and a flexible connection engaged with the lid and fixed with the support to cause the lid to open the holder on the tilting of the same. 20

2. A device of the character described comprising a support for mounting upon and horizontally to a vertical wall and having spaced parallel side members, hangers depending from said side members, a garbage pail holder swingingly supported by said hangers, air cushioned tensioning means connected with the said holder and said support to return the holder to normal upright position after tilting thereof, a cover for said holder and hinged at the rearmost point thereof. 30

3. A device of the character described comprising a support for mounting upon and horizontally to a vertical wall and having spaced parallel side members, a garbage pail holder swingingly supported by said hangers, air cushioned tensioning means connected with said holder and said support to return the holder to normal upright position after tilting thereof, a cover for said holder and hinged at the rearmost point thereof, and means connected with the hangers and said holder to limit the tilting movement of the latter. 40

4. In a device of the character described, a support, a swinging garbage pail holder in the support, a lid hinged to the holder, a connection between the support and said lid for effecting the opening of the holder on the tilting thereof, and means connected with the support and said holder to limit the tilting movement of the latter. 50

5. In a device of the character described, a support, a swinging garbage pail holder in the support, a lid hinged to the holder, a connection between the support and said lid for effecting the opening of the holder on the tilting thereof, means connected with the support and said holder to limit the tilting movement of the latter, and air cushioned tensioning means connected with said holder and said support to return the holder to normal upright position after tilting thereof. 60

JOHN COLAIZZI.
